UNITED STATES PATENT OFFICE.

LEN ALBERT BANTA, OF CLEARFIELD, PENNSYLVANIA.

DESIGN FOR A REFRIGERATOR.

Application filed December 29, 1922. Serial No. 4,751. Term of patent 7 years.

To all whom it may concern:

Be it known that I, LEN ALBERT BANTA, a citizen of the United States, residing at Clearfield, in the county of Clearfield and State of Pennsylvania, have invented a new, original, and ornamental Design for a Refrigerator, as shown in the accompanying drawing and described in the following specification.

The figure is a perspective view of a refrigerator showing my new design.

I claim:

The ornamental design for a refrigerator as shown.

LEN ALBERT BANTA.
